UNITED STATES PATENT OFFICE.

GEORGE A. KERESTES, OF PITTSBURGH, PENNSYLVANIA, ASSIGNOR TO NOVELTY AMUSEMENT CO., OF PITTSBURGH, PENNSYLVANIA, A CORPORATION OF DELAWARE.

MOTION-PICTURE AND TARGET APPARATUS. REISSUED

1,389,877.

Specification of Letters Patent. Patented Sept. 6, 1921.

Application filed May 20, 1919, Serial No. 298,406. Renewed December 1, 1920. Serial No. 427,657.

To all whom it may concern:

Be it known that I, GEORGE A. KERESTES, a citizen of the United States, residing at Pittsburgh, in the county of Allegheny and 5 State of Pennsylvania, have invented certain new and useful Improvements in Motion-Picture and Target Apparatus, of which the following is a specification.

My invention relates to improvements in 10 motion picture machines and also to motion picture target apparatus of the class employing a target, a picture projecting device, and electrical connections between the target and projector actuated by the impact of a bullet 15 or projectile on the target for automatically stopping the movement of the picture film.

In the employment of motion picture machines, it is desirable at times to present a 20 still picture on the screen instead of a moving picture, thus, for example, where the moving picture is being utilized in connection with a lecture or a talk, or more frequently, when the motion picture machine is being employed in connection with a target 25 apparatus wherein the projecting device is stopped by means actuated by the impact of a bullet or by firing a shot, etc.

Prior to my invention, the stoppage of the 30 picture film in order to produce the still picture has been accomplished by stopping all of the moving parts of the machine, the result being that the machine soon becomes destroyed or inefficient, due to the sudden stoppage of its rapidly moving parts.

An object of the present invention is to 35 provide simple and efficient means for stopping the movement of a picture film for the purposes above described, without affecting or stopping the rapidly moving parts of the 40 machine.

A further object of my invention is to provide a new and improved motion picture target apparatus.

In the accompanying drawings which 45 illustrate an application of my invention,

Figure 1 is a rear elevational view of a motion picture machine embodying my invention;

Fig. 2, a side elevational view of the machine;

Fig. 3, an enlarged detail view particularly showing the film feed sprockets, the lower one being the intermittently driven

sprocket, and the means for stopping the rotation of said sprockets;

Fig. 4, a detail view, partly in section, the section being taken on line 4—4 of Fig. 1;

Fig. 5, a detail view of the Geneva movement employed; and

Fig. 6, a diagrammatic view showing the 60 target apparatus, timing mechanism, a portion of the moving picture mechanism, and the electrical connections between the said parts.

Referring to the drawings, A designates 65 a moving picture machine, B a preferably screen onto which the pictures are designed to be projected; and C a target or back wall.

The moving picture machine, as illustrated, includes a casing 1 of any suitable construction, the lens 2, and a shutter 3. As shown, the movable parts are driven by means of an electric motor 4, although the machine may be operated manually. The main drive shaft 5 is connected with the 70 motor by means of a belt 6 and drive wheel 7. 8 designates a fly wheel mounted on shaft 5. The film tape 9 is designed to be fed down through the machine from reel 10, over opening 11 of frame 12, in the usual 80 manner.

The film passes over and is fed through the machine by the feed wheels or sprockets 13 mounted on a shaft 14, and the usual intermittently driven wheels or sprockets 85 15, the latter being mounted on shaft 16. Shaft 14 is driven from the main drive shaft 5 through gearing 17 and 18 and the shaft 16 is also driven from shaft 5. The means illustrated for driving the intermittently 90 driven shaft 16 include a star wheel 19, of the Geneva type, mounted on and keyed to the shaft 16, a shiftable sleeve element 20 carrying a pin 21 and having a clearance space 22 for the star wheel and a groove 23, 95 said element 20 being mounted and slidable on drive shaft 5. The shutter 3, as illustrated, is driven from shaft 5 by means of gearing 24.

The elements above described, with the 100 exception of the shiftable sleeve element 20, are of known construction and are arranged to operate a motion picture machine in the usual manner. It should also be understood that my invention is not limited to the combination of these elements with means for 105

arresting the movement of the film without stopping the motor and the rapidly moving parts of the machine, for my invention may be embodied in motion picture machines 5 having mechanism differing considerably from that shown.

A characteristic and important feature of my invention is the provision of means co-operating with the intermittently driven 10 film feed wheel or sprocket, or said wheel or sprocket and the other film feed wheel or sprocket of a motion picture machine, whereby the movement of the film through the machine may be stopped for a desired period 15 of time without stopping or affecting the other movable parts of the machine.

The mechanism employed for stopping the rotation of the intermittently driven shaft 16 or the feed wheels or sprockets 13, 20 in addition to the element 20, includes a movable bent downwardly extending arm 25, pivotally secured to the framework of the machine with its fulcrum point at 26. Arm 25 carries a pin 27, the latter being entered 25 in the groove 23 of element 20; the lower portion of the arm is bent as shown at 28, and said portion 28 is formed with a flange or bent up portion 29. 30 designates a stop element mounted on shaft 5, the function of 30 which is to prevent an inward movement of arm 25 and the consequent shifting of element 20 until the desired instant. That is to say, the element 20 should be permitted to slide only when a complete picture is 35 shown on the screen. Said stop element 30 is formed with a collar 31 having a laterally extending slot 32 through which the flange 29 of arm 25 may pass to permit the inward movement of said arm and element 40 20. The movement of arm 25 is effected by a horizontally extending rod 33 having one end attached to arm 25 at 34 and its opposite end connected with a link 35, the latter being pivotally secured to a portion of the 45 frame.

As illustrated and as preferred, the movement of the rod 33 is effected by means of a bar 36 connected with and adapted to be moved by the core 37 of a solenoid 38; and 50 for this purpose bar 36 is provided with a pin 39 entered in the pivotally mounted link 35. It is evident, however, that bar 36 may be moved by other than electrical means.

For the purpose of stopping the rotation 55 of the feed sprockets 13 on shaft 14, when desired, I provide a clutch mechanism 40. Said clutch mechanism, as shown, is operated by means of the bar 36, a pivotally supported link 41 secured at 42 to the frame, 60 a rod 43 extending from the link to the clutch, and a pin 44 co-operating with the link.

The parts just described are particularly 65 illustrated in the detail view of Fig. 3, and as there shown, are arranged to drive the

film feed wheels. An upward movement of the bar 36 will release the clutch mechanism 40 and also shift the slideable element 20, thereby throwing pin 21 free of the star wheel 19 as the former revolves with the 70 element 20. A movement of the bar 36 in the opposite direction or into the position shown by Fig. 3 will permit the film to be fed through the machine, with the usual intermittent movement. 75

The mechanism herein described provides simple and efficient means for automatically stopping for a predetermined period the movement of the film, thereby enabling a still picture to be shown on the screen, this 80 being accomplished without stopping the other movable parts of the motion picture machine.

In the present invention I have shown the motion picture machine and the above described means for stopping the picture film in connection with a target apparatus and electrically operated means between the target and the machine designed to be operated by the impact of a bullet or projectile on 90 the target. 85

The target structure 45 is similar to the target structure shown in an application filed by me December 18, 1918, Serial No. 267,341. As shown herein, it includes a 95 plurality of loosely suspended impact plates 46, said plates being suspended from rods 47 and adapted to be moved inwardly the desired distance by the impact of a bullet. Each plate is provided with a push rod 48 100 adapted to strike against an angle plate 49, the latter being mounted on a tilting bar 50. Bars 50 also carry a vertical row of plates 51 having divided ends adapted to straddle a vertically movable switch actuating rod 105 52. Rod 52 is provided with a series of pins 53 which engage the divided ends of plates 51. It will be understood that an inward movement of an impact plate will tilt a bar 50, and that when this occurs, the switch actuating rod 52 will be raised. Raising the rod is designed to complete an electric circuit for the purpose of effecting certain operations hereinafter described. 110

In the embodiment of my invention as 115 shown by the drawings, the electrical current employed in connection with the various parts of the apparatus is obtained from the main line 60.

An upward movement of the switch actuating rod 52 caused by the impact of a bullet against one of the plates 46, acting through the means above described, will operate a toggle arm 61 pivotally secured to an arm 62 of the frame. Toggle arm 61 engages the lower end of rod 52, and, upon the upward movement of said rod, arm 63 of toggle 61 is moved to make contact with an enlarged portion 64 disposed at the lower end of a pivotally mounted curved arm 65. 120 125 130

Arm 65 is fulcrumed at 66 and has its upper end attached to a slotted and horizontally extending arm 67.

The elements just described constitute a portion of an electrical switch device and timing apparatus, said switch and timing apparatus being made the subject of a companion application filed by me May 20, 1919, Serial No. 298,405.

10 As shown herein, 68 designates a fixed contact strip of the switch mechanism and 70 a movable switch arm designed to be thrown by the movement of the horizontally movable arm 67. The connection between the 15 arm 67 and the switch arm 70 includes a pivotally mounted arm 71 secured at 72 to the frame of the machine and pivotally connected with arm 67 by a pin 73. Arm 71 at its upper end is provided with a pin 74 20 adapted to operate in a slot 75 of the switch arm 70. As shown, a movement of bar 67 to the left will cause switch arm 70 to move from stop block 69 to contact point 68, thereby completing an electric circuit to 25 solenoid 38 of the motion picture machine; and at the same time completing an electric circuit to a motor 76 of the timing mechanism.

The timing mechanism includes, in addition to the motor, motor shaft 77 having a worm 78 thereon, a pinion wheel 79 meshing with said worm, a striking pin 80 carried on the pinion, a pivoted arm 81 having its ends divided and engaging a pin passed 35 through arm 67, and a pivotally mounted arm 82 secured to the divided arm 81.

It will be understood that the closing of the circuit 90 leading to solenoid 38 energizes the core 37 of the said solenoid to 40 raise the bar 36, thereby throwing out the clutch mechanism 40 and moving the slideable element 20 on drive shaft 5 to disconnect said element from the star wheel carried on the intermittently driven shaft 16, 45 thus stopping the film feed wheels 13 and 15. The time the movement of the film is arrested depends upon the speed of rotation of the wheel 79. It will be understood that with the closing of the circuit 90 to the solenoid 38 a circuit 91 is completed to the motor 76, thereby starting said motor and the timing mechanism.

The speed of the motor is controlled by means of a regulator 92. From the drawings and a reference to the companion application above mentioned, it will be understood that the period of rest of the film will depend on the time it takes for the striking pin 80 to make a revolution, for it will 50 be noted that upon each revolution of striking pin 80 said pin will come into contact with rod 82, thereby causing the switch arm 70 to be brought from engagement with contact point 68 into engagement with stop 55 block 69.

For the purpose of moving the screen or curtain B, I provide a solenoid 93, the core 94 of which is employed for moving a dog 95 on a ratchet wheel 96 mounted on the shaft of the screen reel. The circuit 97 for 70 solenoid 93 is also made and broken by means of the striking pin 80 on pinion 79. This is effected by employing a pivotally mounted switch arm 98 adapted to be moved into contact with contact plate 99.

100 designates a movable shutter preferably made of colored mica, this shutter being adapted to be moved over and away from the opening 11 (see Fig. 1) by the movement of the bar 36 and the connections 80 between said bar and shutter. Said connections include a toggle arm 101 carrying a pin 102, a pivotally mounted plate 103, the latter having a slotted portion 104 into which the pin 102 is entered. The function 85 of the shutter 100 is to change the color of the picture thrown onto the screen during the time the movement of the film is arrested. It will be understood that the shutter may be omitted if desired, although I find it of 90 advantage for the purpose of enabling the bullet holes made in the screen B to be more readily seen, and also this shutter greatly diminishes the heat generated by the light rays.

What I claim is:

1. In apparatus of the class described, a motion picture machine having a shutter and a film feed mechanism, a target, and means actuated by the impact of a bullet on 100 the target and coacting with the film feed mechanism for arresting the movement of the film without stopping the shutter.

2. In apparatus of the class described, a motion picture machine having a shutter 105 and a film feed mechanism, a target, and means actuated by the impact of a bullet on the target and coacting with the film feed mechanism for arresting the movement of the film without stopping the shutter, said 110 means including an electric circuit between the target and the picture machine.

3. In apparatus of the class described, a motion picture machine having a shutter and an intermittent film feed mechanism, a 115 target, and means actuated by the impact of a bullet on the target and coacting with the intermittent film feed mechanism for arresting the movement of the film without stopping the shutter.

4. In apparatus of the class described, a motion picture machine having a shutter and an intermittent film feed mechanism, a target, and means actuated by the impact of a bullet on the target and coacting with the intermittent film feed mechanism for arresting the movement of the film without stopping the shutter, said means including an electric circuit between the target and the picture machine.

5. In apparatus of the class described, a motion picture machine having a shutter and an intermittent film feed mechanism, a common driving shaft, said film feed mechanism including a driven shaft, a film feed wheel and a star wheel mounted on said driven shaft, a slideable element on the driving shaft adapted to be moved into and out of engagement with the star wheel, a target, and means actuated by the impact of a bullet on the target for independently arresting the movement of the intermittent feed mechanism whereby the movement of the film is arrested without stopping the shutter.
6. In apparatus of the class described, a motion picture machine having a shutter and an intermittent film feed mechanism, a common drive shaft, said film feed mechanism including a driven shaft, a film feed wheel and a star wheel mounted on said driven shaft, a slideable element on the driving shaft adapted to be moved into and out of engagement with the star wheel, a target, and means actuated by the impact of a bullet on the target for independently arresting the movement of the intermittent feed mechanism whereby the movement of the film is arrested without stopping the shutter, said latter means including an electric circuit between the target and picture machine.
7. In apparatus of the class described, a motion picture machine having a shutter, intermittent film feed mechanism, a common drive shaft for the shutter and film feed mechanism, said film feed mechanism including a driven shaft, and coacting mechanism on said shafts, said mechanism including a slideable element on one of the shafts, a target, and electrically operated means actuated by the impact of a bullet on the target for independently arresting the movement of the intermittent feed mechanism whereby the movement of the film is arrested without stopping the shutter.
8. In apparatus of the class described, a motion picture machine having a shutter and a film feed mechanism, a target, and means actuated by the impact of a bullet on the target and coacting with the film feed mechanism for arresting the movement of the film without stopping the shutter, said means including a normally inactive electric circuit between the target and the motion picture machine.
9. In apparatus of the class described, a motion picture machine having a shutter and intermittent film feed mechanism, a common drive shaft, said mechanism including a driven shaft, and coacting means on said shafts, a target, and means actuated by the impact of a bullet on the target for arresting the movement of the film without stopping the shutter, said means including a normally inactive electric circuit between the target and the motion picture machine.
10. In apparatus of the class described, a motion picture machine having a shutter, intermediate film feed mechanism, and a driving shaft, said mechanism including a driven shaft, a slideable element on the driven shaft, and means for shifting the slideable element to stop the movement of the film without stopping the movement of the shutter.
11. In apparatus of the class described, a motion picture machine having a shutter, intermittent film feed mechanism, and a driving shaft, said feed mechanism including a driven shaft, and coacting mechanism on said shafts, said mechanism also including a slideable element on one of the shafts, and electrically operated means for shifting the slideable element to stop the movement of the film without stopping the shutter.
12. In apparatus of the class described, a motion picture machine having a shutter and intermittent film feed mechanism, and means coacting with said mechanism for stopping the movement of the film without stopping the shutter.
13. In apparatus of the class described, a motion picture machine having a shutter and intermittent film feed mechanism, and electrically operated means coacting with said mechanism for stopping the movement of the film without stopping the shutter.
